DESIGN FOR A JUMPING STICK

Arthur E. Bausenbach, Buffalo, N. Y.

Application October 25, 1946, Serial No. 134,218

Term of patent 3½ years

(Cl. D34—5)

To all whom it may concern:

Be it known that I, Arthur E. Bausenbach, a citizen of the United States, residing at Buffalo, in the county of Erie and State of New York, have invented a new, original, and ornamental Design for a Jumping Stick, of which the following is a specification, reference being had to the accompanying drawing, forming a part thereof.

Figure 1 is the front elevation of the jumping stick embodying my design. Figure 2 is a side view thereof. Figure 3 is a top plan view of the same.

I claim:

The ornamental design for a jumping stick, substantially as shown.

ARTHUR E. BAUSENBACH.
